UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, ENGLAND.

BREECH MECHANISM OF SEMI-AUTOMATIC AND QUICK-FIRING GUNS.

1,088,212.

Specification of Letters Patent. Patented Feb. 24, 1914.

Original application filed April 1, 1912, Serial No. 687,576. Divided and this application filed April 11, 1913. Serial No. 760,350.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in Breech Mechanism of Semi-Automatic and Quick-Firing Guns, 10 of which the following is a specification.

This invention relates to the breech actuating mechanism of semi-automatic guns of the kind that can be converted into quick firing guns; in this type of gun we have already proposed to provide two catch devices one of which is adapted to lock the breech actuating hand lever to the gun when the latter is to be worked semi-automatically and the other to lock the hand lever to the 20 block actuating spindle when the gun is to be worked as a quick firer.

The chief object of the present invention is to so construct and arrange the said catch devices that the one for causing the hand lever to be locked to the actuating spindle cannot be moved into its locking position without effecting the disengagement of the other catch device. In this manner it is impossible when the gun is working semi-automatically for the parts to be damaged as a result of the hand lever being unintentionally locked to the gun and to the actuating spindle at the same time. The connection between the catch devices is also such that 30 the catch device for locking the hand lever to the gun is capable of being disengaged without disturbing the catch device appertaining to the actuating spindle, so that if the breech block should fail to return to the 35 closed position when the gun is working semi-automatically, the actuating hand lever can be moved into a position such that the last mentioned catch device engages with the actuating spindle, whereupon the latter can 40 be moved by hand.

In order that the said invention may be clearly understood and readily carried into effect we will describe the same more fully with reference to the accompanying drawings in which:—

Figures 1 and 2 are respectively an end and a side elevation, Figs. 3 and 4 are sectional end and side elevations, and Fig. 5 is

a plan, showing a constructional form of our improvements.

55

A is a portion of the breech end of the gun, B the breech actuating hand lever, B' its handle and B' the block actuating spindle.

C represents the catch device for locking the hand lever to the actuating spindle 60 (herein referred to as the "quick firing catch") and D represents the catch device for locking the hand lever to the gun (herein referred to as the "semi-automatic catch").

65

In the type of breech actuating mechanism to which our invention is shown applied by way of example, the actuating spindle B' is provided with a toothed segment B² that engages with a spring controlled 70 rack contained in a case or cavity B³ forming part of the breech actuating hand lever B, in a similar manner to that set forth in the specification of our application for British Patent No. 19847 of 1910. The quick 75 firing catch C is, in the example shown, in the form of a lever pivoted at c to the hand lever B, and its forward end is adapted to engage in a recess b² of the toothed segment B². In the construction shown in the drawings, the outer end of the said quick firing catch C engages with a forked member e constituting part of a grip lever E pivoted 80 at e^x to the handle B^x of the actuating hand lever B. This grip lever has a cam projection e² (Fig. 3) adapted, when the said handle is grasped, to coöperate with a spring controlled plunger constituting the aforesaid semi-automatic catch D. This catch is 85 in the example shown formed with a slot d to receive the rear end of the quick firing catch and the forked member e of the grip lever E, and is also recessed to receive a floating 90 plug or loose piston E' and a spring e' controlling the same. The said plug is furnished with a roller e^{2x} which engages with the lower surface of the cam projection e² 95 on the grip lever. The upper surface of the said cam projection bears against a roller e^{3x} carried by the catch D.

100

When it is desired to actuate the breech mechanism by hand for the initial opening of the breech prior to semi-automatic working, the handle B^x of the actuating hand lever B is grasped and the grip lever E displaced. The cam projection e² on the grip 105

lever by its engagement with the roller e^{sx} causes the semi-automatic catch D to be lifted out of engagement with its pocket A^x in the gun against the resistance of the 5 spring e' in the said catch, the floating plug E' being prevented from lifting under the influence of the spring by the engagement of the roller e^{sx} with the under surface of the cam projection e^2 . At the same time 10 the forked member e of the grip lever displaces the quick firing catch C into engagement with the recess b^2 in the pinion B^2 on the actuating spindle B' . The breech can then be opened, and when the pressure on 15 the grip lever is released, the aforesaid spring e' causes the catches C, D to resume their normal position, the usual beveled face d^o formed on the nose of the semi-automatic catch D enabling the said nose to engage 20 with the pocket A^x in the gun when the hand lever is returned to the normal position for closing the breech. When the gun is working as a quick firer, the grip lever E is retained in its displaced position by the 25 pressure thereon of the gunner's hand during the opening and closing of the breech.

When the gun is working semi-automatically the semi-automatic catch D is in engagement with its pocket A^x , and, owing to 30 the aforesaid connection between the said catch and the quick firing catch C, the latter is positively retained out of engagement with the recess b^2 of the pinion B^2 . If the actuating spring of the semi-automatic gear 35 should fail to return the breech block to the closed position, owing for example to a tight cartridge case, the semi-automatic catch D is lifted by means of a milled head D^o thereon out of engagement with the pocket 40 A^x in the gun (this movement taking place

without moving the quick firing catch C owing to the elongated slot d in the semi-automatic catch D) and the hand lever can then be moved into a position which is such that when the grip lever E is displaced, the quick firing catch C can engage with the recess b^2 in the pinion B^2 whereupon the breech can be operated by hand.

What we claim and desire to secure by Letters Patent of the United States is:—

1. In the breech actuating mechanism of semi-automatic and quick firing guns, the combination with the breech actuating hand lever and the block actuating spindle, of a pivoted lever on the hand lever, means for retaining said pivoted lever out of engagement with the spindle, a plunger carried by the hand lever for engaging with the gun and means whereby the movement of the lever into engagement with the spindle displaces the plunger out of engagement with the gun.

2. In the breech actuating mechanism of semi-automatic and quick firing guns, the combination with the breech actuating hand lever, and the block actuating spindle, of a pivoted lever on the hand lever, a grip lever on said hand lever for co-operating with said pivoted lever, a spring controlled plunger in the handle of said hand lever, a roller on said plunger and a projection on said grip lever for engaging with said roller.

In testimony whereof we affix our signatures in presence of two witnesses.

ARTHUR TREVOR DAWSON.
GEORGE THOMAS BUCKHAM.
